COMBINED HOSE AND NOZZLE

Clarence W. Borden, Trenton, N.J., assignor to Goodall
Rubber Company, Trenton, N.J.

Filed Oct. 14, 1966, Ser. No. 4,275

Term of patent 14 years

(Cl. D23—34)

FIG. 1

FIG. 2

FIG. 3

FIG. 4

FIG. 5

FIG. 6

FIG. 7

FIG. 8

FIGS. 1 and 2 are views of two embodiments of the combined hose and nozzle; and

FIG. 3 is an enlarged fragmentary view of the pattern of indentations used in the embodiment of FIGS. 1 and 2. FIGS. 4-8 show fragmentary views of further patterns of indentations according to this design of a hose with integral nozzle.

The FIGS. 1 and 2 appearances have been shown broken away for indeterminate length.

I claim:

The ornamental design for a combined hose and nozzle, substantially as shown and described.
